UNITED STATES PATENT OFFICE.

ALFRED J. KELLOGG, OF NEWBERG, OREGON.

COMPENSATING TRUCK FOR RAILWAY-CARS.

1,092,814.

Specification of Letters Patent.

Patented Apr. 7, 1914.

Application filed July 29, 1913. Serial No. 781,810.

To all whom it may concern:

Be it known that I, ALFRED J. KELLOGG, a citizen of the United States, residing at Newberg, in the county of Yamhill and State of Oregon, have invented certain new and useful Improvements in Compensating Trucks for Railway-Cars, of which the following is a specification.

My invention relates to trucks for railway cars, and has for its object to compensate for, or reduce to a minimum, the torsional strain to which the axles and bearings are subject,—and to obviate the invariable frictional and shearing actions of wheels and their flanges upon the outer rails of curves in a line of railroad, which occur by reason of the conditions wherein the outer wheels of a truck have a circle of a larger arc to traverse than that of the wheels of the inner and consequently shorter circle, with the resultant slipping and grinding of the latter, and similar heavy friction and tendency to shear of the former.

The object of my invention is to provide a device of this kind that is simple in construction, durable, and less expensive in first cost than are the standard trucks in present use,—and this improvement may be considered as a further amplification and development of my Patent No. 999,192, bearing the date of July 25, 1911.

While my first invention had for its object to eliminate axles extending between, or rigidly connected with wheels arranged in pairs, one for each rail of the track,—and individual truck-sections for each rail of the track,—such sections carrying a plurality of wheels, and a separate axle for each wheel, with independent journals and bearings therefor,—separate king-bolts whereby the separate truck-section riding upon one rail may swivel independently of that riding upon the other rail,—the improvement forming the subject matter of this application provides primarily for a simplified and efficient brake-bar, which also serves as means of spacing the wheels to the gage of the tracks, in cooperation with the beam,—and a novel structure of journal-box, which features will be hereinafter fully set forth and specifically claimed.

Other objects and advantages of my invention will be made clearly apparent in the following specification taken in connection

with the accompanying drawings which form part of this application:

Figure 1 is a plan view of my invention; Fig. 2 is a side elevation of same; Fig. 3 is an end elevation and section of same; said section being taken on line B B of Fig. 2; Fig. 4 is a longitudinal vertical section through the journal-box; Fig. 5 is a transverse section of same; Fig. 6 is a perspective of the brake-beam; Fig. 7 is a perspective of the bolster center-plate; Fig. 8 is a similar view of the truck center-plate, and Fig. 9 is a section taken on line A A of Fig. 2.

Now referring to the drawings (in which like characters of reference indicate like parts), the numerals 2 and 2^a indicate frames which are spaced apart by means of spreaders 3, bolted adjacent the ends of said frames and prevented from longitudinal movement by means of lips 4, which are cast integral with the webs of the frames, as best illustrated in Fig. 9. Placed intermediate said frames are bolster center-plates 5, which are pivoted to transverse apertures in said frames by means of trunnions 6; resting on said bolster center-plates are truck center-plates 7, with flanges 8, so formed as to limit the horizontal movement of frames 2. It will be noted that the sides of said truck center-plates that pass longitudinally intermediate the frames form arcs of a circle, and when the frames contact with the ends of said arcs the horizontal travel ceases, but it is seldom if ever, that the shearing motion will reach these extremes. The lower end of said bolster center-plates and the upper ends of said truck center-plates have turned therein ball-races 9, which register with each other,—and in which are placed steel balls in order that the trucks may easily and instantly move horizontally when said trucks shear. Resting on said bolster center-plates and securely pivoted to same is a beam 10, through which the king-bolts 11, pass downwardly and through the bolster center-plates and truck center-plates and through bosses 10^a which are integral with the lower portions of said beam, said beam serving in part as a means of spacing the trucks to the gage of the rails, as well as a rest for the car body.

By observing Fig. 2 it will be noted that the webs of the frames have longitudinal slots 12 therein, through which pass trun-

nions 13, to distances predetermined by gibs 14^a—14^b, respectively; said gibs 14^a being integral with brake-beam 14, while gibs 14^b are detachable in order that it may be removed to allow the ends of said brake-beam to pass through slots 12 in frames 2^a. Formed intermediate of gibs 14^a and 14^b, are guides 14^c, which register with slots 12 in frames 2^a; said slots serving as bearings 10 in which said guides travel. Projecting outwardly from said guides are arms 13^a, which also rest on the edges of said slots and which position the wheels to the gage of the rails. These brake-beams and their 15 members are a salient feature of my present invention,—and which supersedes the ordinary form of brake-beam which I have heretofore used. In the longitudinal central portions of said brake-beams are slots 15, to 20 which are fastened the ordinary means of connecting and operating such parts and need not be here described, as they form no part of this invention. The trunnions 13, form pivotal bearings for brake-shoes 17. 25 Revolvably mounted in journal-boxes 18, are axles 19, to which are fixed intermediate the frames, wheels 20; each axle operating independently of the others. The outer portions of said journal-boxes have pivoted 30 thereto the ordinary form of cover, 21,—and within said journal-boxes are ribs 22, which are integral with the walls thereof, and of which lugs 22^a form a part, said lugs being arranged to prevent lateral motion of the 35 axle, and serve to hold brasses 23, in fixed positions; this feature being another improvement on my prior invention above mentioned.

My invention may be constructed of any 40 materials and made in any size deemed suitable for all the requirements of such a device,—and while I have illustrated and described a preferred form of construction and combinations of elements considered essential in materializing the same, I wish to 45 include in this application all mechanical equivalents and substitutes that may be fairly considered to come within the scope and purview of my invention as set forth in the appended claims.

Having thus fully described my invention so that others skilled in the art to which it appertains may be able to construct and use the same, what I claim and desire to secure 50 by Letters Patent, is:—

1. In a device of the character described, frames spaced apart, means to secure said frames in such spaced relation, a transversely fixed connection between the frames 60 forming the truck section, longitudinally movable brake-beams secured intermediate the inner frames, said brake-beam also serving to space apart the upper portions of the truck sections, trunnions attached to said 65 brake-beams, brake-shoes attached to said

trunnions, transverse apertures in each of said frames, truck center-plates pivotally attached within said apertures by means of trunnions, said trunnions being integral with said truck center-plates, journal-boxes 70 attached to the frames, an axle revolvably mounted in each journal-box, a wheel fixed on each axle, and means to prevent lateral motion of said axle, substantially as described.

2. In a device of the character described, frames spaced apart by means of spreaders, said spreaders being bolted adjacent the ends of said frames, a beam passing transversely of said trucks, said beam being firmly secured to the truck center-plates, said truck center-plates being secured intermediate the upper portions of said frames, bolster center-plates pivoted intermediate said frames, by means of trunnions which 85 are integral therewith, ball-races in said truck center-plates and bolster center-plates, balls in said ball-races, said balls spacing the bolster center-plates and truck center-plates apart, a king-bolt passing downwardly 90 through said beam and through the center-plates and through lugs, said lugs being integral with the lower ends of said beam, journal-boxes attached to the frames, an axle revolvably mounted in each journal-box, 95 a wheel fixed to each axle, and means to prevent lateral motion of said axle attached within said journal-box substantially as described.

3. In a device of the character described, 100 frames spaced apart by means of spreaders, said spreaders being bolted adjacent the ends of said frames, a beam passing transversely of said trucks, guides integral with said beams, gibs integral with the lower portions 105 of said guides; detachable gibs on the upper portions of said guides, said guides being slidably mounted in the slots of the inner frames, said gibs serving as means to prevent longitudinal motion of said brake-beams and to space the trucks to the gage 110 of the rails, said beam being firmly secured to the truck center-plates, said truck center-plates being pivoted intermediate the upper portions of said frames, a flange on each of 115 said truck center-plates the longitudinal vertical edges of which form arcs of a common circle and serve as guides to the horizontal movement of the car-body, bolster center-plates pivoted intermediate said frames by 120 means of trunnions which are integral therewith, ball-races in said truck center-plates and bolster center-plates, balls in said ball-races, said balls spacing the bolster center-plates and truck center-plates apart and also 125 serving to keep the car-body in an upright position when the trucks shear, a king bolt passing downwardly through said beam and through the center-plates and through lugs, said lugs being integral with the lower ends 130

of said beam, said king bolt also serving to prevent any downward thrust of the brake-beam, journal-boxes attached to the frames, an axle revolubly mounted in each journal box, a wheel fixed to each axle, and means within said journal-box to prevent lateral motion of said axles, substantially as described.

In testimony whereof I hereunto affix my signature in the presence of two subscribing 10 witnesses.

ALFRED J. KELLOGG.
